UNITED STATES PATENT OFFICE

2,295,016

DISPOSABLE ABSORBENT SANITARY PAD

Marion E. Scribner, Denver, Colo.

Application February 7, 1942, Serial No. 429,900

1 Claim. (Cl. 128—290)

This invention relates to improvements in disposable sanitary napkins.

One object of this invention is to produce a sanitary napkin or absorbent pad for use with a suitable supporting belt, which can be secured to the belt without the use of pins and in such a manner that it can be readily applied and removed.

Another object is to produce a pad of great absorptive power and of such material that it can be readily disposed of after it has been used, thereby obviating the necessity of cleaning.

A further object is to produce an absorbent pad or sanitary napkins of said construction that a deodorant powder can be applied thereto and positioned thereon.

A still further object is to produce an absorbent pad of such construction that it can be manufactured by an automatic machine and therefore at a low cost.

Another object is to produce a pad that shall have a layer of nonabsorbent fibrous material near its lower surface to minimize the danger of soiling the supporting portion of the belt and a still further object is to produce a pad having a pocket for containing and positioning a deodorant powder and which can be used with disposable diapers as well as with sanitary napkins.

Having thus briefly pointed out the objects of the invention, the same will now be described in detail, and for this purpose reference will be had to the accompanying drawing in which the invention has been illustrated, and in which:

Figure 1 is a perspective view showing the pad in position on a supporting member attached to a belt;

Figure 2 is a top plan view of the pad, a portion being broken away to better disclose the construction;

Figure 3 is a section taken on line 3—3, 40 Figure 2;

Figure 4 is a longitudinal section taken on lines 4—4, Figures 2 and 3;

Figure 5 is a fragmentary section of a portion of the pad similar to that shown in Figure 4, but to a somewhat enlarged scale;

Figure 6 is a bottom view of the pad;

Figure 7 is a section taken on line 7—7, Figure 1;

Figure 8 is a perspective view showing the pad in the position it occupies while being applied to or removed from the supporting member;

Figure 9 is a view showing a diaper constructed in accordance with this invention; and

Figure 10 is a section taken on line 10—10, Figure 9.

In the drawing reference numeral 11 designates a belt having a front suspending member 12 and a rear suspending member 13. The lower end of member 13 terminates in a supporting pad 14 whose front end is provided with hooks 15 for engagement with the loops of the elastic 16 in the manner shown in Figure 8.

10 The belt and supporting member form no part of this invention and have been shown merely for the purpose of more clearly explaining the same.

The pad that forms the subject of this invention and which has been illustrated in Figures 15 2 to 6, inclusive, is formed from fibrous material, such as soft fibered absorbent paper. The outer surface of the pad is formed by a sheet 17 of absorbent fibrous material which, in the embodiment illustrated, is provided with two pleats

20 18 and 19. Pleat 18 is preferably wider than pleat 19 and the latter serves principally as a closure for the pocket 20 that is provided for the purpose of containing and retaining a deodorant powder. The outer member 17 is

25 formed by special machinery or by hand, into a tubular shape, the edges, which have been indicated by reference numeral 21, are spaced apart as shown in Figure 3 and are connected by means of a strip of paper 22 having its outer surface

30 provided with an adhesive, for example, rubber cement. Strips of paper having such adhesive surface are commonly sold for the use of draftsmen who employ them instead of thumb tacks because the adhesive does not dry but remains

35 tacky for a long time, which is an important consideration in the present invention. Positioned within the envelope and on top of the strip 22 is a layer 23 of cotton which has been treated with oil or in some other way so as to render it only slightly absorbent; this layer is to some extent moisture proof. The remainder of the pad above the layer 23, is formed from a plurality of layers of absorbent fibrous material of the kind above indicated. This material has been designated by reference numeral 14.

The pad has been designed so as to be suitable for manufacture in long strips by means of automatic machinery and means is provided for cutting the strips into sections of the proper length. 45 It is desirable that the ends of the pad be slightly compressed so as to taper and that they be held lightly in this shape by some suitable means. It is also quite desirable to secure the pleat 18 at the ends in such a way that it will retain its position during handling and form a pocket for

the reception of the deodorant powder. In order to compress and secure the ends in compressed position by the same operation of the machine that effects the cutting, the attachment is effected by means of two punches that penetrate the material forming holes 25, two of which have been shown at each end of the pad. Due to the very fibrous nature of the material, and to its great softness, the action of the penetrating punch is to pull the fibers downwardly into a somewhat tubular form as indicated by reference numeral 26 in Figure 5. This serves to temporarily interconnect the several layers and holds them with sufficient strength to prevent their opening due to the slight amount of handling to which they are subjected. The tape 27 formed from some suitable material such as "Cellophane" is positioned over the adhesive surface of strip 22 in the manner shown in Figure 6 so as to guard against material coming into adhesive contact with the strip during handling and merchandising. Before the pad is used, the strip 27 is removed by exerting thereon a pull in the manner indicated in Figure 6. After the covering strip 27 has been removed, the pad is positioned on the support 14, in the manner shown in Figure 8, and pressed against the fibrous surface of the latter, whereupon the adhesive material will come into operative contact with the upper surface of support 14 and attach the pad thereto in a manner quite obvious from an inspection of Figure 8. Due to the action of the adhesive strip, the use of safety pins or other attaching means can be dispensed with since the adhesive strip exposed along the lower surface of the pad serves to hold the latter in position with sufficient force to prevent its accidental displacement even when the hooks at the front of the supporting member 14 are disconnected from the elastic loops.

It is apparent that pads constructed in the manner above described and from absorbent fibrous material have, in addition to their large capacity for absorbing fluid, another advantage, namely, that the smooth fibrous surface prevents chafing and discomfort during use. The presence of the cellulose cotton serves to some extent to prevent the soiling of the supporting member 14.

Attention is called to the fact that the pad 14 is filled with a fibrous material that has been designated by reference numeral 28 and that this rests on a layer 29 of "Pliofilm" or some other thin, waterproof material. If the supporting pad 14 does become soiled, it is possible to launder the same so as to make it suitable for further use.

Particular attention is called to the presence of the pocket 20 that has been provided for the reception of a deodorant powder. Due to this

construction, the deodorant powder can be applied in sufficient amount to become effective and will be held in proper position by the two pleats 18 and 19, pleat 19 serving more or less as a closure for the pocket 20.

In Figures 9 and 10, a slightly different shaped pad has been shown which is intended to serve as a diaper for babies. The triangular pad shown in Figure 9, which has been designated by reference numeral 30, has its upper surface provided with two pleats 18a and 19a which serve to form a pocket 20a for the reception of a deodorant powder. Aside from shape, and the fact that the diaper is not provided with a strip of adhesive corresponding to 22 in Figure 3, the diaper has the important characteristics of the pad above described.

A diaper formed from absorbent fibrous material and provided with a pocket for deodorant powder is very convenient and is readily disintegrated when subjected to the action of water, wherefore it is admirably suitable for use as a disposable diaper which obviates the necessity of laundering.

Absorbent pads of the kind and construction above described can be manufactured at a comparatively low cost, almost entirely by automatic machinery and since very little, if any cotton, is employed, the material necessary is readily available and therefore avoids the delay incident to obtaining the ordinary cotton material usually employed for this purpose.

Particular attention is called to the presence of the adhesive surface 22 and the pocket 20 for the reception of the deodorant powder. The presence of the cellulose cotton layer 23 between the absorbent filling 24 and the adhesive strip 22 is also of considerable importance as by the use of this material a pad is obtained that retards, to a great extent, the penetration of fluid through the bottom thereof.

Having described the invention, what is claimed as new is:

45 A disposable absorptive sanitary pad comprising, an envelope formed from a sheet of fibrous material bent to form a tube, the adjacent edges of the sheet being spaced apart, means for connecting the adjacent edges comprising a strip of material having its outer surface provided with an adhesive, said strip being positioned within the envelope in overlapping relation to the spaced adjacent edges, the adhesive material exposed between the adjacent edges serving as means for attaching the pad to a supporting member, and 50 55 a filling of absorbent material in the envelope.
